UNITED STATES PATENT OFFICE.

HENRY B. SARGENT, OF NEW HAVEN, CONNECTICUT, ASSIGNOR TO
SARGENT & COMPANY, OF NEW HAVEN, CONNECTICUT, A COR-
PORATION OF CONNECTICUT.

PLANE.

No. 818,472.

Specification of Letters Patent.

Patented April 24, 1906.

Application filed August 15, 1904. Serial No. 220,834.

To all whom it may concern:

Be it known that I, HENRY B. SARGENT, of the city and county of New Haven and State of Connecticut, have invented new and useful Improvements in Planes, of which the following is a full, clear, and exact description when taken in connection with the accompanying drawings, which form a part thereof, and in which—

10 Figure 1 represents a side elevation of a plane embodying the invention; Fig. 2, a bottom view of the same; Fig. 3, an enlarged plan view; Figs. 4 and 5, longitudinal sectional views on line 4 4 of Fig. 3, the parts 15 being shown in different positions; Figs. 6 and 7, top and side detail views, respectively, of the adjustable mouthpiece; Fig. 8, a bottom detail view of the adjusting-cam, and Fig. 9 a transverse vertical section of the 20 plane-bottom on line 9 9 of Fig. 3.

In all figures similar letters of reference represent like parts.

This invention relates to planes, and has for its object the production of a plane having a novel, simple, and efficient throat adjustment; and to this end it consists in the improvements and combinations of parts set forth and claimed hereinafter.

Referring to the drawings for a more particular description, the part designated by the letter A represents the plane-bottom, and B the side walls. C designates the throat, and D the frog or plane-iron seat. E designates the bit or plane-iron, and F the cap, with the cap-screw G. H is the cam-lever, I the lateral adjustment-lever, and K the adjusting-screw controlling the longitudinal adjusting-lever L. These parts may be of any suitable construction and are not 40 part of my improvement.

As shown in Figs. 2, 4, and 5, the bottom of the plane is cut away in front of the throat for the reception of a slide or mouthpiece M. A circular perforation N is provided in the 45 forward part of the plane-bottom with an inwardly-projecting flange O, Fig. 9. A disk P is adapted to fit in said perforation and rest on said flange and has on its under side a cam or circular depending protuber- 50 ance Q, eccentric to the center of the disk. A finger-piece R projects from the periphery of the disk P, and through the center of the disk is a perforation S.

On the upper side of the slide or mouthpiece M are lugs T, distant from each other 55 the length of the diameter of the cam Q, Figs. 4 and 5, while between them is an upwardly-projecting screw V, adapted to extend through the perforation S in the disk P for the reception of a clamping-nut W, 60 which also forms the forward knob of the plane. The perforation S in the disk P is considerably wider than the diameter of the screw V, so that the disk may have a limited movement about the screw without contact 65 therewith.

The operation of the device is as follows: When it is desired to change the adjustment of the throat from the position shown in Figs. 2, 3, and 4, the clamping-nut W is slightly 70 turned to loosen the disk P and slide M, and the disk P is turned the necessary distance by means of the finger-piece R. The cam then bears against the rear lug T on the slide M and pushes the slide rearward, as shown 75 in Fig. 5. The slide M then contracts the throat C the desired amount, and the parts are secured by screwing the clamping-nut W down on the screw V, so that the slide will be held against the under side of the forward 80 end of the bottom A of the plane and the disk forced down on the flange O in the perforation N. To open the throat, it is only necessary to unscrew the nut W and loosen 85 the parts to operate them in the reverse direction.

It will be seen that the cam depending from the disk engages the mouthpiece in an immediately adjacent plane, so that the operation is direct, and the coacting parts will 90 be protected by the disk from dust, chips, or the like.

Having now described my invention, what I claim, and desire to secure by Letters Patent, is—

1. In a plane, the combination with a stock, of a throat in the bottom thereof, a sliding mouthpiece for varying the size of said throat, a disk fitted in a circular seat to rotate on said stock and having a depending 100 cam between said stock and said mouthpiece adapted to engage said mouthpiece to operate the same, and protected by said disk, and means for locking said mouthpiece.

2. In a plane, the combination with a 105 stock, of a throat in the bottom thereof, a

sliding mouthpiece for varying the size of said throat, a disk fitted in a circular seat to rotate on said stock and having a depending cam between said stock and said mouthpiece 5 adapted to engage projections on said mouthpiece in an immediately adjacent plane to operate the same, and protected by said disk, and means for locking said mouthpiece.

3. In a plane, the combination with a 10 stock, of a throat in the bottom thereof, a sliding mouthpiece for varying the size of said throat, a disk fitted in a circular seat to rotate on said stock and having a perforation and a depending cam between said stock and 15 said mouthpiece adapted to engage integral projections on said mouthpiece in an immediately adjacent plane to operate the same, and protected by said disk, and means for locking said mouthpiece, including a screw- 20 threaded post on said mouthpiece projecting through said perforation in said disk, and a nut on said post adapted to bind said disk on said stock to prevent movement thereof.

4. In a plane, the combination with a 25 stock, of a throat in the bottom thereof, a sliding mouthpiece for varying the size of said throat, a disk mounted on said stock and having a depending cam and a perforation,

oppositely - disposed integral lugs on said mouthpiece adapted to be engaged by said 30 cam, a screw-threaded post on said mouthpiece projecting through said perforation in said disk in which it is capable of lateral play, and a nut on said post adapted to bind said disk on said stock to prevent movement of 35 said mouthpiece, the nut being arranged to overlap the wall surrounding the aperture of the disk.

5. In a plane, the combination with a 40 stock, of a throat in the bottom thereof, a sliding mouthpiece for varying the size of said throat, a disk fitted in a circular seat to rotate on said stock and having a depending cam between said stock and said mouthpiece 45 adapted to engage integral projections on said mouthpiece in an immediately adjacent plane to operate the same and protected by said disk, a projecting finger-piece on the upper surface of the disk, and means for locking said mouthpiece from movement.

In witness whereof I have hereunto set my hand on the 11th day of August, 1904.

HENRY B. SARGENT.
